UNITED STATES PATENT OFFICE

112,754

DESIGN FOR A TEXTILE FABRIC OR SIMILAR ARTICLE

Eugenio Filippi, Fairview, N. J.

Application October 22, 1938, Serial No. 80,628

Term of patent 3½ years

To all whom it may concern:

Be it known that I, Eugenio Filippi, a citizen of the United States, residing in Fairview, county of Bergen, and State of New Jersey, have invented a new, original, and ornamental Design for a Textile Fabric or Similar Article, of which the following is a specification, reference being had to the accompanying drawing, forming part thereof.

The figure is a plan view of a textile fabric or similar article showing my new design.

I claim:

The ornamental design for a textile fabric or similar article, as shown.

EUGENIO FILIPPI.
